UNITED STATES PATENT OFFICE.

FREDERICK C. ROCKWELL, OF WEST HARTFORD, CONNECTICUT.

DESIGN FOR A COMPOSITION FIRE-KINDLER.

SPECIFICATION forming part of Design No. 34,677, dated June 18, 1901.

Application filed March 11, 1901. Serial No. 50,770. Term of patent 7 years.

To all whom it may concern:

Be it known that I, FREDERICK C. ROCKWELL, a citizen of the United States, residing at West Hartford, in the county of Hartford and State of Connecticut, have invented and produced a certain new and useful Design for a Composition Fire-Kindler, of which the following is a specification.

In the accompanying drawings, which form a part of the specification, Figure 1 shows an end view of a composition fire-kindler having my design, and Fig. 2 shows a side view of the same.

As shown in the drawings, the leading or material feature of my design is a body that viewed from the side shows parallel edges and ends at right angles with the edges and that viewed from the ends shows a blunt-pointed

stellate configuration. The cross-sectional configuration shows the composition fire-kindler to have five round-ended radiations 3, with five rounded intermediate depressions 4. Through the kindler is an opening 5, that in cross-sectional outline simulates the star-shaped cross-sectional outline of the exterior of the kindler.

Having described my invention, what I claim as new, and desire to secure by Letters Patent, is—

The design for a composition fire-kindler herein shown and described.

FREDERICK C. ROCKWELL.
